BICYCLE

David L. Carey, 10937 Garden Grove Ave., and Robert Q. Riley, 15525 Nordhoff St., both of Los Angeles County, Calif.

Filed Jan. 18, 1965, Ser. No. 83,479

Term of patent 14 years

(Cl. D90—8)

FIGURE 1 is a side elevation of the bicycle;

FIG. 2 is a top plan view;

FIG. 3 is a bottom or under side view;

FIG. 4 is a rear elevation; and

FIG. 5 is a front elevation.

The dominant feature of our design resides in those portions shown in full lines.

We claim:

The ornamental design for a bicycle, substantially shown and described.
